Primary Examiner — Ania Aman(74) *Attorney, Agent, or Firm* — Foley & Lardner LLP(57) **CLAIM**

We claim the ornamental design for an engine component, as shown and described.

DESCRIPTION

FIG. 1 is a top, front, right perspective view of the claimed design;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a rear elevation view thereof.

The claimed design is shown in solid lines in the drawings. The broken lines formed by equal length dashes shown in the drawings are for the purpose of illustrating portions of the engine component that form no part of the claimed design. The broken lines formed by unequal length dashes (i.e., dash-dot) shown in the drawings are for the purpose of defining bounds of the claimed design.
